UNITED STATES PATENT OFFICE

141,751

DESIGN FOR A CIGARETTE ROLLING MACHINE

Charles S. Combs, Irondequoit, N. Y., assignor of one-half to Donald R. Browne, Rochester, N. Y.

Application March 1, 1945, Serial No. 118,203

Term of patent 3½ years

(Cl. D85—7)

To all whom it may concern:

Be it known that I, Charles S. Combs, a citizen of the United States, residing in the town of Irondequoit, in the county of Monroe and state of New York, have invented a new, original, and ornamental Design for a Cigarette Rolling Machine, of which the following is a specification, reference being had to the accompanying drawing, forming part thereof.

Fig. 1 is a perspective view of a cigarette rolling machine viewed from one direction, showing my new design; and

Fig. 2 is a perspective view of the same, viewed from a different direction.

I claim:

The ornamental design for a cigarette rolling machine, substantially as shown.

CHARLES S. COMBS.
